his Attorney

Patented Aug. 9, 1927.

UNITED STATES PATENT OFFICE.

THOMAS MANEY, OF LOUISVILLE, KENTUCKY.

GUARD-RAIL FASTENING.

Application filed June 18, 1926. Serial No. 116,895.

My invention relates to an improvement in guard rail fasteners.

The present invention affords a very strong and secure fastening more particularly for wooden ties, and has several advantages over former constructions, it being more flexible in general application, because it is my purpose to furnish the guard rail which is applicable to any section of main rail, with proper relationship to the main rail which is obtained by varying the position of its seat in the brace-chair.

One feature of this invention includes a double-headed reversible rail section, the heads being so shaped as to admit of a good form of splicing, and so that when excessive wear takes place, the heads may be reversed by simply removing a key and rolling the rail over, so that it does not have to be turned end for end, making it very advantageous for use in tunnels, subways, and all close quarters. As the stresses are different from those of the main rail, it is designed to resist lateral strain instead of vertical strain, and as this guard-rail bears no load, it may run higher in carbon composition, which increases its resistance to wear. It is designed to meet the stresses peculiar to it, with the minimum amount of metal.

Thus my present invention includes a compensating plate, a double-headed reversible guard-rail, and a chair-seat or brace of peculiar design and construction, adapted for the purpose, and a key by means of which the rail is made secure in the chair-seat or brace.

In the accompanying drawings:

Fig. 1 is a transverse section;

Fig. 2 is a fragmentary plan view showing the main rail and guard-rail in position, and other parts;

Fig. 3 is a plan view showing the plate and chair-seat or brace;

Fig. 4 is a section showing a splice for the guard-rail; and

Fig. 5 is a side view of a fish-plate.

The numeral 1 represents the main rail, and 2 is a tie-plate upon which the main rail is seated, one edge being held against the rib 3, and this edge is held down by a spike 4 extending through a hole 5 provided for it in the tie-plate 2.

The numeral 6 represents the guard-rail, the heads of which are alike, rendering it reversible, so that when one head becomes

unduly worn, the rail may be rolled over and reversed in position without the necessity of turning it end for end, thereby making it most desirable for installation in narrow places like tunnels, subways, and the like.

The ordinary splice of the guard-rail is shown in Figs. 4 and 5, in which the fish-plates 7 are held by the bolts 20. The inner edge of the base flange of the main rail 1 and the guard-rail 6 are supported and held securely by the chair-seat or brace 8. This has a base 9 which rests upon the tie-plate 2, as viewed in Fig. 1. On the lower side of the base, a tongue 10 projects downwardly and outwardly, and is adapted to extend into a slot 11 in the tie-plate and engage the sloping under edge 12 thereof as shown in Fig. 1, while the edge 13 of the chair-seat or brace extends above the base flange of the main rail. The chair-seat or brace is thus inserted in the space between the edge of the base flange of the main rail and the tie-plate shoulder 14, the tongue 10 engaging the surface 12 of the slot 11 in the tie-plate, and the projection 13 the main rail base flange as just explained, after which the lag-bolts 15 are inserted through the holes 16 in the base 9, thence through the corresponding holes in the tie-plate, and screwed on into the tie 17 below.

The guard-rail 6 is seated in the brace-seat 18 of the chair seat or brace, where it is held by a key 19 driven between the flange and the overhang of the chair-seat or brace, as shown in Fig. 1. The chair seat or brace and the key may be made either of forged steel or malleable iron. The key, however, is preferably of malleable iron, and terminates in a more or less slender elongated end, which is adapted to be bent over after the key is in place as illustrated in Fig. 2.

In this way, a very rigid fastening is provided for the main rail and guard-rail.

The fitting of the chair-seat or brace between the base-flange of the main rail and the tie-plate shoulder locks the main rail securely to the tie-plate. The two lag-screws extending into the tie on either side of the chair seat or brace hold the latter securely in place, and the tie-plate to the tie. The guard-rail is then laid in the brace-seats where it is confined rigidly by driving in the keys above the flange of the guard-rail.

The fitting of the base of the chair-seat or brace between the tie-plate shoulder and

edge of the main rail confines the main rail against lateral movement. The tongue 10 passing through the slot 11 punched in the tie-plate against the sloping edge of the slot, 5 with a portion of the chair-seat or brace extending over the edge of the base flange has the effect of securely locking the main rail to the tie-plate so that no spiking or other fastening is required on that side. The lag- 10 screws being driven into the tie on either side of the chair-seat or brace through the holes provided therefor in the base and tie-plate afford auxiliary fastening for the chair-seat or brace, but their main purpose 15 is to prevent the tie-plate from moving on the tie.

I claim:

1. In a device of the character described, 20 the combination of a main rail, a tie plate therefor, and a chair seat or brace seated upon said tie plate and abutting against the edge of the main rail flange, said chair seat or brace having a flange extending outwardly therefrom and overlapping the main rail flange for holding said main rail in position.

2. In a device of the character described, 30 the combination of a main rail, a tie plate therefor, a chair seat or brace seated upon said tie plate and having a base abutting against the edge of the main rail flange, said chair seat or brace having an outwardly extending flange spaced apart from the tie plate for overlapping the main rail flange and cooperating with the base to hold said main rail in proper position, and a guard rail carried by said chair seat or brace.

3. In a device of the character described, 40 the combination of a main rail, a tie plate having a slot therein, and a chair seat or brace seated upon said tie plate and having a base abutting against the edge of the main rail flange, said chair seat or brace having an outwardly extending flange spaced apart from the tie plate for overlapping the main rail flange, and the base having a tongue 45 extending into the slot for cooperating with the outwardly extending flange to hold the main rail in proper position.

4. A guard having the heads thereof arranged out of alignment with each other and connected by a web extending at an obtuse angle to the heads.

5. A reversible guard rail having the heads thereof connected by a web, one of 55 said heads being enlarged on one side of the web, and the other head being enlarged on the opposite side of the web.

6. In a device of the character described, 60 the combination of a main rail, a chair seat or brace having a guard rail seat therein, a reversible guard rail supported in said seat, said chair seat or brace extending over a base flange of the guard rail in spaced apart relation therewith, and a key inserted

above the base flange of the guard rail and between said flange and the chair seat or brace for holding the guard rail rigidly in its seat.

7. In a device of the character described, 70 the combination of a tie plate having a slot therein, said slot having a wall thereof inclined, a main rail mounted on the tie plate, and a chair seat or brace abutting against the main rail and having a tongue extending 75 into the slot in the tie plate and against the inclined surface for securing the main rail in proper position.

8. Means of the character described including a flanged tie-plate having a shoulder and a ridge, and provided with a slot, 80 one wall of which is inclined, a main rail secured against the ridge, a chair-seat or brace fitted between the base flange of the main rail and the shoulder and having a 85 tongue which extends through the slot in the tie-plate and against the inclined surface, the chair-seat or brace having a projection which extends over the base flange for securing the main rail in place, and 90 means for securing the chair seat or brace rigidly in place.

9. Means of the character described including a flanged tie-plate having a shoulder and a ridge, and provided with a slot, 95 one wall of which is inclined, a main rail secured against the ridge, a chair-seat or brace fitted between the base flange of the main rail and the shoulder and having a tongue which extends through the slot in the 100 tie-plate and against the inclined surface, the chair-seat or brace having a projection which extends over the base flange for securing the main rail in place, means for 105 securing the chair seat or brace rigidly in place, and a guard-rail held by the chair-seat or brace.

10. Means of the character described including a flanged tie-plate having a shoulder and a ridge, and provided with a slot, 110 one wall of which is inclined, a main rail secured against the ridge, a chair-seat or brace fitted between the base flange of the main rail and the shoulder and having a tongue which extends through the slot in the 115 tie-plate and against the inclined surface, the chair-seat or brace having a projection which extends over the base flange for securing the main rail in place, means for securing the chair seat or brace rigidly in 120 place, and a reversible guard-rail held by the chairseat or brace.

11. Means of the character described including a flanged tie-plate having a shoulder and a ridge, and provided with a slot, 125 one wall of which is inclined, a main rail secured against the ridge, a chair-seat or brace fitted between the base flange of the main rail and the shoulder and having a tongue which extends through the slot in 130

the tie-plate and against the inclined surface, the chair-seat or brace having a projection which extends over the base flange for securing the main rail in place, means 5 for securing the chair seat or brace rigidly in place, a reversible guard-rail held by the chair-seat or brace, and a key for holding the guard-rail securely seated.

12. Means including a tie-plate having a 10 slot, one edge of which is undercut, a main rail resting on the tie-plate, a chair seat, one edge of which is constructed to embrace the undercut edge of the slot, and the adjacent edge of the main rail base, whereby 15 to fasten securely one edge of the rail, and

means for securing the chair seat or brace to the tie plate below.

13. Means including a tie-plate having a slot, one edge of which is undercut, a main rail resting on the tie-plate, a chair seat, 20 one edge of which is constructed to embrace the undercut edge of the slot, and the adjacent edge of the main rail base, whereby to fasten securely one edge of the rail, means for securing the chair-seat or brace to the 25 tie plate below, a reversible guard-rail held in the chair-seat or brace, and means for securing the tie-plate rigidly in position.

In testimony whereof I affix my signature.
THOMAS MANEY.
